(57) **CLAIM**

The ornamental design for an air freshener picture frame, as shown.

DESCRIPTION

FIG. 1 is a front elevational view of an air freshener picture frame showing my new design;

FIG. 2 is a perspective view thereof;

FIG. 3 is a top plan view thereof;

FIG. 4 is a rear elevational view thereof; and,

FIG. 5 is a side elevational view thereof, the opposite side being the same as the side shown.
